COOK TOP GRILL OR SIMILAR ARTICLE

Kenneth E. Rawald, Anaheim, Calif., assignor to Norris Thermador Corporation, Los Angeles, Calif., a corporation of California

Filed May 7, 1965, Ser. No. 85,165

Term of patent 14 years

(Cl. D81—25)

FIG. 1.

FIG. 2.

FIG. 3.

FIG. 4.

FIGURE 1 is a top plan view of a cook top grill or similar article with the cover closed showing my new design;

The counter, shown in broken lines, is included for illustrative purposes only.

I claim:

The ornamental design for a cook top grill or similar article, as shown and described.
